UNITED STATES PATENT OFFICE.

WILLARD S. BASS, OF WILTON, MAINE.

MOCCASIN.

1,139,153.

Specification of Letters Patent.

Patented May 11, 1915.

Application filed September 4, 1914. Serial No. 860,242.

To all whom it may concern:

Be it known that I, WILLARD S. BASS, a citizen of the United States, residing at Wilton, in the county of Franklin and State 5 of Maine, have invented certain new and useful Improvements in Moccasins; and I hereby declare that the following is a full, clear, and exact description thereof, reference being had to the accompanying drawings, which form part of this specification.

This invention relates to foot wear, and particularly to moccasins or shoe packs, and its object is to provide a moccasin in which the toe piece will be attached to the vamp 15 in a novel manner, which will render the moccasin neater in appearance and more water-tight and less liable to ripping.

In the present invention the vamp and toe pieces are united by a peculiar lap seam, 20 stronger and tighter than the usual hand or butt seam. Heretofore in moccasins, shoe packs, etc., it has been usual to join the toe piece or top portion of the upper to the vamp by means of a hand or butt 25 seam, in which the toe piece and vamp, after being properly skived, are turned outward, butted together and fastened by stitches showing upon the outer surface of both vamp and toe piece. This form of butt 30 seam is not so strong and not so tight as a lap seam, and cases are frequent in which such butt seams open up sufficiently to admit water, or break away entirely before the moccasin is worn out.

It has, heretofore, been impractical to use 35 lap seams to sew the vamp to the toe piece, because when the vamp is turned up around the forepart of the last to meet the toe piece a "fullness" is produced, *i. e.* the edge 40 of the vamp is longer than the edge of the toe piece to which it must be sewn. It has therefore been necessary to gather or pucker the vamp so that its edge, when finished, is no longer than that of the toe piece. The 45 difficulty in doing this gathering properly has heretofore prevented the use of a lap seam for this purpose.

By the present invention I am enabled 50 to make a moccasin or similar article of foot wear having the toe piece connected to the vamp with a peculiar combination lap and butt or hand seam which I will now explain more fully with reference to the accompanying drawings, in which:—

55 Figure 1 is a perspective view of a moccasin made with the novel seam. Fig. 2 is

an enlarged section on line 2—2, showing a partially completed seam; and Fig. 3 is an enlarged section on line 3—3, showing a completed seam.

I will explain the invention as applied to a moccasin. In manufacturing moccasins I proceed as follows: The vamp 1 may be cut in the usual manner. The top or toe piece 2, or the entire upper if desired, is 65 cut in the usual manner but sufficiently large to lap over the adjacent edges of the vamp as indicated at 2^c Fig. 2. The vamp and top portions are placed upon a last; the vamp is then gathered in and sewn to 70 the top portion or toe piece 2 by stitching 3 in the usual manner of lasting and sewing moccasins; that is, the toe piece and vamp after being properly skived are turned outward and fastened by stitches 3 extending 75 transversely through the edge of the vamp and through the toe piece; but such stitching is at a point somewhat remote from the edge of the toe piece leaving a projecting portion or flap portion beyond this seam, as 80 indicated at 2^c in Fig. 2. This portion 2^c of the toe piece then projects over the adjacent edges of the vamp and over the lower edges of the stitches, the edges of this portion 2^c being then free and unattached, see Fig. 2. 85 The moccasin is then withdrawn from the last and the projecting or lapped portion 2^c of the toe piece is turned down onto the vamp and secured thereto by stitches 4 passing through the vamp and toe piece and 90 showing only on the outer surface of the vamp. The stitches 4 may be sewn by hand or machine, I prefer to sew them with a machine making lock stitches.

A moccasin or other foot wear having the 95 vamp and top united in the above described manner possesses the advantages, (1) of permitting proper gathering of the vamp by the hand seam; (2) of permitting the use 100 of a lap seam to unite the vamp and the toe piece, which in itself is stronger and tighter than a hand seam; and (3) of combining a hand seam and a lap seam which reinforce and strengthen each other.

It will be seen by reference to the drawings that this construction gives an unusually attractive finished appearance to the toe of the moccasin; only the portion of the rows of stitching 3 in the toe piece showing externally and the rough or butt edge of the 110 vamp being entirely covered and concealed by the lapped portion 2^c of the toe piece;

and the stitching 4 showing at the edge of the lapped portion of the toe piece insures a rigid and permanent attachment of the parts together, makes a water-tight lap seam, and also imparts an ornamental appearance to the moccasin.

What I claim is:—

1. A moccasin having a vamp of the usual form and a toe-piece large enough to project 10 over the adjacent edge of the vamp; said toe-piece being fastened to the vamp first, by a seam in which the stitches pass directly through the edge of the vamp and through the toe-piece some distance from its edge, 15 and secondly, by a lap seam in which the stitches pass through the vamp and through the projecting portion of the toe-piece which overlaps the edge of the vamp and covers the stitches of the first seam on the outer 20 side of the vamp.
2. A moccasin having a vamp and a toe-piece projecting over the adjacent edge of the vamp, and secured thereto by stitches passing through the toe-piece and through 25 the edge of the vamp so that a portion of the toe-piece projects beyond said point of attachment and the edge of the vamp and laps a short distance onto the surface of the vamp covering the edge of the vamp and the 30 stitches underlying it on the outer side of the vamp; the toe-piece being further fastened to the vamp by a seam in which the stitches pass through the vamp and the projecting edge of the toe-piece.
3. A moccasin having a vamp of usual 35 form, a toe piece large enough to project

over the adjacent edges of the vamp, said toe piece being sewed to the vamp by a seam passing directly through both vamp and toe piece so that the stitches appear only on the 40 outer surface of the toe piece, the edges of the toe piece projecting beyond such seam and the projecting lapped portion of the toe piece being stitched to the vamp parallel with the first seam.

4. A moccasin having a toe piece and a vamp gathered and stitched to the toe piece in the usual manner, said toe piece having a projecting portion lapped onto the vamp and secured thereto by stitches passing 50 directly through both the vamp and the projecting portion of the toe piece so that the stitches appear on the outer surface of the toe piece and the inner surface of the vamp.

5. A moccasin having a vamp of the usual 55 form and a toe-piece projecting over the adjacent edge of the vamp, said toe-piece being fastened to the vamp by a seam formed by stitches passing through the edge of the vamp and through an overlying portion of 60 the toe-piece some distance from the edge of the latter; said toe-piece being further fastened to the vamp by a lap seam in which the stitches pass through the vamp and the projecting edge of the toe-piece.

In testimony that I claim the foregoing as my own, I affix my signature in presence of two witnesses.

WILLARD S. BASS.
